UNITED STATES PATENT OFFICE.

BUNNY M. RYDZY, OF MICHIGAN CITY, INDIANA.

COMBINATION FLASH-LIGHT AND CIRCUIT TESTER.

Application filed June 29, 1923. Serial No. 648,529.

My invention belongs to that general class of devices known as flash lamps or lights and relates more particularly to a combined flash light and tester, which is convenient 5 for use by electricians, mechanics, motorists and the like, for testing fuse plugs, electric light wiring, ignition wiring and generally as a trouble shooter, as well as a simple and convenient trouble light or the like for the 10 purposes for which flash lights are generally used. The invention has among its objects the production of a device of the kind described that is simple, convenient, durable, attractive, compact, efficient and satisfactory 15 for use wherever found applicable.

Many other objects and advantages of the construction herein shown and described will be obvious to those skilled in the art from the disclosure herein given.

20 To this end my invention consists in the novel construction, arrangement and combination of parts herein shown and described, and more particularly pointed out in the claim.

25 In the drawings, wherein like reference characters indicate like or corresponding parts,

Fig. 1 is a sectional view through my improved device;

30 Fig. 2 is a view of one of the contacts, showing a novel form of protecting cap;

Fig. 3 is a similar view showing another type of cap; and

35 Fig. 4 is a similar view illustrating another type of protecting cap.

Referring to the drawings, in which the preferred embodiment of the invention is shown, I have illustrated a flash lamp similar to those in general use, it being understood 40 that the details of the lamp construction and battery container may be modified without departing from the general construction of my improvement.

As shown, 1 represents a casing of suitable material such as metal, provided with 45 an end cap 2 which is preferably removable and with a threaded flange 3 arranged to receive a lens retainer 4. Arranged within the casing is the battery 5 consisting of one 50 or more cells, depending upon the size and design of the casing, which need not necessarily be cylindrical as shown. The particular casing 1 shown is of metal and may therefore be used as one of the conductors or contacts, the same being electrically con-

nected with the battery by the spring 6, which also maintains the battery against displacement and against one of the terminals of the lamp. The opposite end of the battery is provided with the usual terminal 7 60 arranged to contact with the terminal 9 on the lamp 8, the shell 10 on the lamp also serving as a conductor, it being understood that the terminals 9 and 10 are connected with the lamp filament. The lamp as shown 65 is arranged to be carried by the reflector member 11, which may be insulated from the casing by the insulating member 15. I have shown a lens 12 secured in place by the retainer 4, the lens also serving to secure 70 the reflector in place. There is provided a switch member 14 arranged to be controlled from the exterior of the casing by the button or slide 13. When the slide is moved up member 14 contacts with the 75 reflector which is in electrical contact with the shell 10, thereby closing the circuit and causing the lamp to be lighted, thereby indicating that the battery is alive, as well as permitting the lamp to be used for 80 lighting purposes.

There is in addition provided one or more terminals which are normally a part of an open circuit against which a device to be tested may be placed, closing the circuit and 85 causing the lamp to be lighted, thereby indicating a closed circuit through the device to be tested. In the particular device illustrated, the casing being of metal, it is necessary to provide only one contact, the metallic casing itself serving as a contact and conductor. As shown, I have provided a contact member 17 which is suitably insulated from the casing, but which is provided with a stem 18 extending to the interior of the casing and which carries a spring or contact member 19 arranged to contact with the reflector shell or the shell 10 on the lamp. The particular contact shown is insulated from the casing 1 and washer 20 by insulation 21. 90

In order to prevent the accidental short-circuiting of the terminal 17 with the casing, as for example when the lamp is in a tool box or the like, I have shown in Fig. 2 how a rubber cap 25 may be positioned over the 95 same except during such time as the lamp is used for testing purposes. If desired, the part 20 may be slightly reduced, as indicated at 26, so that the rubber cap is firmly held in place. A piece of rubber tubing may 100 105 110

be provided for the same purpose if desired. In Fig. 3 I have illustrated a metal or fiber cap 27 which may be internally screw threaded and arranged to engage a thread on 5 20' corresponding to 20. In Fig. 4 I have illustrated how a sliding cap 28 might be arranged on the device for the same purpose.

From the preceding it will be obvious that I have provided a flash lamp which may be 10 used in the ordinary manner for the usual purposes, but which may also be used for testing purposes without in any way affecting its use as a lamp. I have also provided a construction that does not involve a radical 15 departure from the present well known types of lamps, so that the devices may be manufactured without reconstructing the entire apparatus.

Having thus described my invention, it is 20 obvious that various immaterial modifications may be made in the same without departing from the spirit of my invention; hence I do not wish to be understood as limiting myself to the exact form, construction,

arrangement and combination of parts 25 herein shown and described, or uses mentioned.

What I claim as new and desire to secure by Letters Patent is:

The combination with a flash light having 30 a control switch, a metallic casing, a metallic reflector insulated from the casing and adapted to engage a terminal of the lamp, of a contact member having a stem projecting through the casing, a washer on the stem 35 tapering inwardly toward the casing, insulation between the stem and washer and between the contact and washer, resilient means at the inner end of the stem engageable with the reflector to form a circuit with 40 the lamp for testing purposes, and an insulating shield fitted over the contact member with its inner portion contracting over the tapering portion of the washer to prevent 45 accidental displacement of said shield.

In testimony whereof, I have hereunto signed my name.

BUNNY M. RYDZY.
